JOSEPH B. DUNLAP AND WILLIAM D. BRYAN, OF TULSA, OKLAHOMA.

SUCKER-ROD-PULLING DEVICE.

1,109,668.

Specification of Letters Patent.

Patented Sept. 8, 1914.

Application filed April 18, 1913. Serial No. 761,973.

To all whom it may concern:

Be it known that we, JOSEPH B. DUNLAP and WILLIAM D. BRYAN, citizens of the United States, and residents of Tulsa, in the county of Tulsa and State of Oklahoma, have made a new and useful Improvement in Sucker-Rod-Pulling Devices, of which the following is a specification.

Our invention is an improvement in devices for lifting tubing, and has for its object to provide a device of the character specified, having means for utilizing the ordinary pumping jack for lifting the sucker rods and tubing from oil wells and the like, thus dispensing with the necessity for a sucker rod pulling machine.

In the drawings:—Figure 1 is a perspective view of one of the improved devices, Fig. 2 is a section on the line 2—2 of Fig. 1, Fig. 3 is a section on the line 3—3 of Fig. 2, and, Fig. 4 is a diagrammatic view showing the operation.

The present embodiment of the invention consists of a bed plate 1, having a central opening 2, extending through the said plate, and the said plate in use is about one square foot in area and one inch in thickness. At each corner of the opening 2 the bed plate 1 is provided with a notch or recess 3, the said notch or recess forming the lower section of a bearing, and each notch or recess extends outwardly from the adjacent corner of the opening.

The notches or recesses 3 at each side of the opening 2 are in alinement, and gripping jaws 4 and 5 are arranged in the opening, the said jaws being connected to the bed plate in the following described manner. Each of the said jaws is provided at one side edge with journal pins 6, the said pins of each jaw being in alinement, and the said pins are adapted to engage or rest in the notches or recesses 3 before mentioned.

The notches or recesses 3 are of suitable depth as shown, and the jaws are rounded to fit the journal pins. An upper bearing section 7 is arranged in each recess above the journal pin, each of the said sections 7 having its end face rounded to fit the journal pin, and forming with the recess 3 a complete cylindrical bearing. Each of the said bearing sections 7 has lateral flanges 8, the said flanges extending in opposite directions, and lapping upon the upper face of the bed plate, and screws 9 are passed through the

said flanges into threaded openings 10 in the bed plate, to hold the bearing section 7 to the bed plate. The gripping jaws 4 and 5 are thus hinged to the bed plate at their outer or remote side edges, and the said plates are of an aggregate width slightly greater than the aggregate length of the opening 2. Each of the said gripping jaws 4 and 5 has its inner side edge beveled from above downwardly as indicated at 11, and at 65 the center of each of the said side edges each gripping jaw is provided with a substantial V-shaped notch 12.

The bracket 13 is arranged at one side edge of the bed plate, the said bracket having an angular lug 14 at one end, secured to the under face of the bed plate by screws 15, and at the other end the bracket has an angular lug 16, extending in an opposite direction to the lug 14, and a lever 17 is pivoted 75 at one of its ends to lug 16, by means of a bolt and nut 18. A slide bar 19 is mounted to slide on the upper face of the bed plate, toward and from the opening 2, and the said bar is provided with a longitudinally extending slot 20, which is engaged by a headed pin 21, connected with the bed plate. Arc-shaped cam fingers 22 and 22^a are connected with the slide bar, the said slide bar having its inner end provided with a tenon 80 23, and the outer ends of the said fingers are pivoted to the tenon by means of a bolt or rivet 24, the fingers being mounted on opposite sides of the tenon. The arrangement is such, that the outer faces of the upper and 85 lower fingers are flushed with the face of the slide bar.

Each of the cam fingers 22 and 22^a is provided with a longitudinally extended slot 25, and each slot is engaged by a headed pin 26 95 on the bed plate. The cam finger 22^a connected to the upper face of the tenon is offset downwardly at its inner end so that the free curved ends of the said fingers are in the same plane and in contact with the upper face of the bed plate.

The cam fingers 22 and 22^a are curved outwardly away from each other toward their inner or free ends, and the said fingers engage beneath the jaws. The lever 17 is 105 pivoted to the outer end of the slide bar 19 by means of a bolt 27, in such manner that when the lever is swung on its pivotal connection the slide bar will be moved toward and from the opening 2 to cause the cam 110

5 fingers 22 and 22^a to swing the free inner edges of the gripping jaws with respect to the hinged edges. When the said lever 17 is swung toward the bed plate the gripping jaws will be swung to cause their inner edges to move upwardly and to separate, while the reverse movement of the lever will permit the jaws to move downward to grip the tubing or sucker rod. The jaws 4 and 5 are thus 10 operated to cause them to grip or to release the pipe to be lowered by means of the cam fingers 22 and 22^a.

In operation, two of the improved devices are made use of for lifting sucker rod and 15 tubing, or for lowering the said sucker rod or tubing in the well casing. In the first place, the jack head is disconnected from the sucker rod, and the stuffing box is then disconnected. Preferably, one of the devices is provided with a longer lever than the other and the said device having the longer lever is placed on top of the well 20 casing, with the tubing or sucker rod to be lifted passing through the opening 2 between the gripping jaws. The second device is then placed on the head of the jack with the rod or tubing to be raised extending through the opening 2 between the jaws. When all is ready, the lever 17 is operated 25 to move the cam fingers outwardly, thus permitting the gripping jaws to swing downwardly at their adjacent side the jaw, thereby, to grip the tubing or the rod. As the jack makes its upward stroke, the rod or 30 tubing will be lifted, usually a distance of approximately 18 inches, and as soon as the jack head moves downward the jaws of the lower plate will automatically grip the rod and hold it until the jack head moves downward for another lift. As the jack head moves downward, the gripping device connected therewith will release the rod or tubing, and will move downward to secure a 35 second grip on the rod or tubing.

40 When it is desired to lower rods or tubing into a well casing, the devices are arranged as above specified, and when the jack moves upward, the upper jaws are held open until the said jaws are about one inch from the top of the stroke of the jack. The jaws are then released and clamp the rod. The final upward movement of one inch is sufficient to release the jaws of the lower device, and the said jaws are then held in 45 lifted position until the jack is near the end of its upward stroke, that is within a distance of one inch of the end of the stroke. The jaws of the lower device are then engaged with the rod or tubing, the further downward movement of the jack releasing the jaws of the upper device.

We claim:—

1. A device of the character specified, 50 comprising a bed plate having a central opening, gripping jaws in the opening, and

hinged to the bed plate, and means for simultaneously swinging the said jaws with respect to the bed plate to move the said free edges upwardly and outwardly, said means comprising a lever pivoted at one 55 end of the bed plate, a slide bar movable toward and from the opening on the upper face of the bed plate, said slide bar being in approximate alinement with the free edges of the jaws, a slidable connection between the said bar and the bed plate, a pivotal connection between the outer end of the bar and the lever, arc-shaped cam fingers, said fingers being oppositely arranged and each finger being pivoted at its outer end 60 to the inner end of the slide bar, the convex edges of the fingers being adjacent and the said fingers diverging toward their free ends, the said free ends extending above the opening of the bed plate and beneath the adjacent gripping jaws, and a slidable connection between each cam finger and the bed plate.

2. A device of the character specified, comprising a bed plate having a central opening, gripping jaws in the opening and said jaws being hinged to the bed plate, and means for simultaneously swinging the said jaws with respect to the bed plate to move the said free edges upwardly and outwardly, 65 said means comprising a lever pivoted at one end of the bed plate, a slide bar movable toward and from the opening on the upper face of the bed plate, said slide bar being in approximate alinement with the free edges 70 of the jaws, a slidable connection between the said bar and the bed plate, a pivotal connection between the outer end of the bar and the lever, cam fingers slidably connected to the bed plate and having their inner ends 75 extending above the opening of the bed plate and beneath the adjacent gripping jaw to raise the said jaws when the fingers are moving toward the opening, and a connection between the said fingers and the slide bar.

3. A device of the character specified, comprising a bed plate having a central opening, gripping jaws mounted in the opening and hinged to the bed plate, and means for simultaneously swinging the said jaws with respect to the bed plate to move the said free edges upwardly and outwardly, 80 said means comprising oppositely arranged and pivotally connected cam fingers mounted to slide on the bed plate toward and from the gripping jaws at one end thereof, and means for simultaneously moving the said fingers, said means comprising a lever pivoted to the bed plate, and a connection between the lever and the cam fingers.

4. A device of the character specified, comprising a bed plate having a central opening, gripping jaws mounted in the opening and hinged to the bed plate, and 85

means for simultaneously swinging the said jaws with respect to the bed plate to move the said free edges upwardly and outwardly, said means comprising oppositely arranged and pivotally connected cam fingers mounted to slide on the bed plate toward and from the gripping jaws at one end thereof, and

means for simultaneously moving the said fingers.
